UNITED STATES PATENT OFFICE.

WILLARD H. FULLER, OF PASSAIC, NEW JERSEY, ASSIGNOR TO THE SCOVILL & ADAMS COMPANY, OF NEW YORK, N. Y.

ROLL-HOLDER.

SPECIFICATION forming part of Letters Patent No. 439,651, dated November 4, 1890.

Application filed May 15, 1890. Serial No. 351,854. (No model.)

To all whom it may concern:

Be it known that I, WILLARD H. FULLER, of Passaic, in the county of Passaic and State of New Jersey, have invented a certain new and useful Improvement in Roller-Holders, of which the following is a specification.

This improvement relates to the apparatus generally termed "roller-holders," which consist of rollers and appurtenant parts acting in combination to successively expose different portions of a sensitized film for photographing.

In the accompanying drawings, Figure 1 is a back view of a roller-holder embodying my improvement, the rear portion of the case being removed. Fig. 2 is a similar view of one end portion thereof without the rollers, which are normally arranged therein. Fig. 3 is a transverse section taken at the plane of the dotted line xx , Fig. 1. Fig. 4 is a section taken at the plane of the dotted line yy , Fig. 1, through the front part of a frame, which is included in the apparatus, and showing certain other parts.

Similar letters of reference designate corresponding parts in all the figures.

A designates a frame consisting of two side pieces a' a^2 , a front plate a^3 , connected to said side pieces, and two cross-bars a^4 a^5 , connected to the rear of the side pieces.

B designates a roller mounted in said frame and having wound upon it a photographic sheet or film C. This roller has cavities in its ends which engage with journals B' B^2 , which are supported in the side pieces of the frame.

The journal B^2 is removable, and is made in the form of a screw and engages with that one of the side frames in which it fits. Hence it may be at any time withdrawn for the purpose of removing the roller B and replacing it by another like it. The journal B' and that end of the roller which receives the same are constructed to interlock, and as this journal is provided with a flange b' , which coacts with a friction-brake b^2 , a resistance is offered by this journal to the rotation of said roller B. Owing to this a tension is produced on the sheet or film in its passage through the frame, and it is caused to lie flat.

D designates a roller journaled in the side pieces of the frame near to the roller B.

E designates a roller journaled to the side

pieces of the frame and near the other end thereof. The sheet or film passes from the forward side of the roller B to and around the rear side of the roller D, thence around the front plate a^3 , and from the latter to the forward side of the roller E. When inserted in the apparatus, the end of the sheet or film is fastened to this roller E, so that by rotating this roller the sheet or film may be drawn across the front plate of the frame from end to end. The roller E is detachably mounted in the frame, so that when the sheet or film, after exposure, shall have been completely wound thereon it will be possible to remove the roller. The roller is supported by journals E' E^2 , the latter of which is made in the form of a screw, so as to be adjustable longitudinally. The journal E' interlocks with the roller E, and is provided with a worm-wheel that engages with a worm F. By rotating the worm motion may be imparted to the roller, and the roller will always be held against rotation after adjustment.

I do not here claim any of the parts which I have thus far described. The improvement for which I here seek protection resides in the means employed for marking the sheet or film.

G designates a swinging rod. It is provided with a number of pin-points g and secured at the ends to arms g' g^2 , which at the inner ends are fastened to a rock-shaft g^3 . This rock-shaft is journaled at the ends in the side pieces of the frame, and may oscillate sufficiently to allow of forcing the pins g through holes in the front plate a^3 of the frame A to puncture the sheet or film and afterward to withdraw said pins from beyond the forward surface of said front plate. On the roller D is a crank wrist or pin d , which once in each rotation of said roller comes in contact with a projection g^4 formed on the rear side of the arm g' . Owing to the projection g^4 on the arm g' the rod G is swung forward with a rapid motion and as quickly released. Whenever the arm g' is released by the passage of the crank wrist or pin beyond the projection g^4 a spring G' forces the bar rearward. This spring consists of a strip fastened at one end to the rear side of the front plate a^3 , and is so bent that at the other end it will impinge against the forward side of the rod G and operate to force

the latter rearward. The crank wrist or pin d is set at such distance from the center of the roller D that the distance between the two rows or sets of punctures g will be about 5 the length of the front plate a^3 of the frame A, and consequently sufficiently large for a picture.

This mechanism for puncturing or marking is very desirable, because it is not at all 10 affected by the increase in the size of the sheet or film wound upon any roller. Owing to this the crank wrist or pin might obviously be placed upon the roller B, if preferred. If this were done, the roller D could be dispensed 15 with and the roller B located in the position which the roller D is shown as occupying.

What I claim as my invention, and desire to secure by Letters Patent, is—

1. In a roller-holder, the combination, with 20 rolls upon which a film is moved, of an outwardly-moving rod having markers, an arm or arms on said rod constructed to contact

with a projection on a roll during the movement of the film, substantially as specified.

2. In a roller-holder, the combination of a 25 rod G, arms $g' g^2$, and a crank wrist or pin operating on one of said arms to move the rod outwardly, substantially as specified.

3. In a roller-holder, the combination of a 30 rod G, arms $g' g^2$, a crank wrist or pin operating on one of said arms to move the said rod outwardly, and a spring for moving the rod inwardly, substantially as specified.

4. In a roller-holder, the combination of a 35 rod G, arms $g' g^2$, one of which is provided with a rearward projection, a crank wrist or pin operating on one of said arms to move the rod outwardly, and a spring for moving the rod inwardly, substantially as specified.

WILLARD H. FULLER.
